APPARATUS FOR WHIPPING CONDUCTORS

Alexander C. Frankwich, Baltimore, Md., assignor
to Western Electric Company, Incorporated,
New York, N. Y., a corporation of New York

Application November 2, 1944, Serial No. 561,611

11 Claims. (Cl. 242—7)

This invention relates to apparatus for whipping conductors, and more particularly to apparatus for whipping conductors with wire.

In the manufacture of communication cords, it is sometimes necessary to whip the ends of conductors of such cords with wire. In such whipping operations, it is necessary that the lengths of the whippings on the ends of the conductors be uniform.

An object of the invention is to provide new and improved apparatus for whipping conductors.

One apparatus embodying the invention includes means for holding a conductor, means for whipping a conductor held by the holding means, means for effecting relative movement between the holding means and the whipping means, and means for indexing the whipping means and the holding means with respect to each other at the end of a whipping operation.

A complete understanding of the invention may be obtained from the following detailed description of a specific embodiment thereof, when read in conjunction with the appended drawings, in which:

Fig. 1 is a front elevation of an apparatus embodying the invention with portions thereof broken away;

Fig. 2 is a vertical sectional view taken along line 2—2 of Fig. 1;

Fig. 3 is an enlarged, fragmentary, vertical sectional view taken along line 3—3 of Fig. 2;

Fig. 4 is an enlarged, fragmentary, vertical sectional view taken along line 4—4 of Fig. 2;

Fig. 5 is a diagrammatical view of an electric circuit for controlling the operation of the apparatus, and

Fig. 6 is a fragmentary, vertical sectional view of the apparatus.

Referring more in detail to the drawings, there is illustrated therein an apparatus for serving wire in neat convolutions upon ends of conductors. This apparatus includes a housing 10 (Fig. 1) enclosing a motor 11, which, when energized, serves to rotate a pulley 12, which drives a belt 13 to rotate a pulley 14 (Fig. 2). The pulley 14 is affixed to a driving clutch disc 15, which is rotatable upon a flanged bushing 16. A manually operable switch 17 (Fig. 1) serves to control the operation of the motor 11, and when the switch is turned on, the motor runs continuously, whereby the pulley 14 (Fig. 2) and the driving clutch disc are rotated continuously.

The flanged bushing 16 is secured in a journal 28 mounted on a standard 21. The bushing 16

serves to support one end of a hollow shaft 22 and the other end of the shaft is supported rotatably in a journal 23 mounted on a standard 24. The shaft 22 is free to rotate in the bushing 16 and the journal 23, but is prevented from axial movement relative thereto by a whipping head 25 of standard construction secured on the outer end of the shaft and by a collar 27 secured on the other end of the shaft.

10 A compression spring 26 is mounted on the shaft 22 between a collar 30 and a collar 31, which latter collar is threaded upon a threaded boss 32 projecting from a brake drum 33. The brake drum 33 is slidable on the shaft 22 but is held 15 against rotation relative thereto by keys 34—34 (Fig. 3). A driven clutch disc 35 (Fig. 2) is secured to the brake drum 33.

A collar 41 (Figs. 2 and 3) mounted loosely on the collar 31 has pins 40—40 projecting from the sides thereof. The pins 40—40 are engaged by a yoke 42, which has slots 43—43 in the arms thereof. The yoke 42 is fastened rigidly to a shaft 44, which is rotatably mounted in bores 45—45 formed in arms 46 and 47 of a frame 50.

15 An arm 51 (Figs. 2 and 3) rigidly secured to the shaft 44 is connected by a link 52 to an arm 53. The arm 53 is fastened securely to a shaft 54 rotatably mounted in bearings 57—57, carried by a motor support 55. An arm 56 (Figs. 1 and 2) secured to the shaft 54 is connected by an adjustable link 60 to a pin 61, which pivotally connects the link 60 to a core 62 of a solenoid 63. A pair of tension springs 64—64 (Fig. 1) are secured to the pin 61 and screws 65—65, which pass through tapped bores 66—66 formed in the motor support 55.

The springs 64—64 hold the core 62 of the solenoid 63 in a raised position when a winding 40 79 (Figs. 1 and 5) of the solenoid is not energized. However, when the winding is energized, the core 62 is drawn downwardly which draws the link 60 downwardly against the action of the springs 64—64. The link 60 through the arm 56 45 then serves to rotate the shaft 54 and the arm 53 in a clockwise direction, as viewed in Fig. 2. This moves the link 52 to the left and causes the shaft 44 to be rotated in a counterclockwise direction through the arm 51, whereby the yoke 42 50 through the pins 40—40 moves the collar 41 to the right. This permits the compression spring 26 to urge the brake drum 33 to the right and causes the driven clutch disc 35 to be carried by the brake drum into an engagement with the driving clutch disc 15. The driving clutch disc

15 then rotates the shaft 22 through the driven clutch disc 35, the brake drum 33, and the keys 34—34. When the winding 70 of the solenoid 63 is de-energized, the springs 64—64, through the system of levers just-described, cause the yoke 42 to thrust the collar 41 toward the left, and the collar 41 moves the brake drum 33 and the driven clutch disc 35 toward the left against the action of the spring 26, whereby the clutch disc 35 is drawn out of engagement with the clutch disc 15.

An arm 71 (Figs. 2 and 3) secured to the shaft 54 is connected by a link 72 to an arm 73 fastened to a shaft 74. The shaft 74 is rotatably mounted in bores 75—75 formed in the arms 46 and 47 of the frame 50. An arm 76 also is secured to the shaft 74 and one end of a tension spring 80 is connected to the outer end thereof. The other end of the tension spring 80 is fastened to an eye 81 secured to one end of a brake band 82. The other end of the brake band 82 is secured to a rod 83 adjustably mounted on a bracket 84.

When the winding 70 (Fig. 2) of the solenoid 63 is not energized, the tension spring 80 holds the brake band 82 into braking engagement with the brake drum 33. But when the winding 70 is energized and the shaft 54 is rotated in a clockwise direction, as viewed in Fig. 2, the arm 71 through the link 72 rotates the arm 73 in a clockwise direction. This rotates the shaft 74 and the arm 76 in a clockwise direction, whereby the spring 80 is lowered and the brake band 82 drops out of braking engagement with the brake drum 33. When the winding 70 of the solenoid 63 is again de-energized, the brake band 82 is brought into braking engagement with the brake drum.

An arm 85 (Figs. 2 and 3) secured to the shaft 54 is connected by a link 86 to an arm 90 mounted on a shaft 91. The shaft 91 is rotatably and slidably mounted in bores 92—92 formed in the arms 46 and 47 (Fig. 3). A compression spring 94 is positioned on the shaft 91 between the arm 46 and a collar 95 secured to the shaft and urges the shaft toward the right, as viewed in Fig. 3. The movement of the shaft 91 toward the right is limited by a collar 96 secured thereto in a position adjacent to the arm 47.

When the winding 70 (Fig. 2) of the solenoid 63 is energized, so that the brake band 82 is moved out of braking engagement with the brake drum 33 and the driven clutch disc 35 is moved into engagement with the driving clutch disc 15, the arm 85 is turned by the shaft 54 in a clockwise direction, as viewed in Fig. 2, whereby the link 86 is raised. The link 86 raises the end of the arm 90 so that an indexing lug 93 secured to the brake drum 33 is free to move past the arm 90. When the winding 70 of the solenoid is de-energized, the clutch disc 35 is moved out of engagement with the clutch disc 15, the brake band 82 is moved into engagement with the brake drum 33, and the arm 90 is rotated in clockwise direction, as viewed in Fig. 2, and is positioned in the path of the indexing lug 93. When this occurs, the brake band 82 slows the rotation of the brake drum 33 and the shaft 22 so that when the indexing lug 93 strikes the arm 90 most of its force has been dissipated. However, any force retained by the revolving brake drum 33 and indexing lug 93 is dissipated when the indexing lug strikes the arm 90. Since the shaft 91 is free to slide in the bores 92—92 against the action of the compression spring 94, any shock imparted by the indexing lug 93 to the arm 90 is absorbed by the com-

pression spring 94 while the rotation of the brake drum 33, the shaft 22 and the whipping head 25 are stopped in positions in which the whipping head is in a position convenient to start a whipping operation.

A worm gear 100 (Fig. 2) rigidly secured to the shaft 22 meshes with a gear 101 having a plurality of teeth 102—108 thereon and secured to a shaft 102. A cam 103 having lobes 104 and 105 formed therein is secured to the shaft 102. A cam follower 106 is mounted on a block 107, which is secured to rods 110 and 111. The rods are mounted slidably in bores 112—112 formed in standards 113 and 114 and have a block 115 secured on the left ends thereof, as seen in Fig. 2, which mounts a work-holder 116. A pair of compression springs 120—120 are mounted between a fixed abutment 119 and collars 121—121 fixed to the rods 110 and 111. The compression springs 120—120 urge the rods 110 and 111 to the right, as viewed in Fig. 2, and maintain the cam follower 106 against the periphery of the cam 103.

When the shaft 22 is rotated, the worm gear 100 is rotated and turns the gear 101 in a clockwise direction, as viewed in Fig. 2. The gear 101 turns the shaft 102, which turns the cam 103 in a clockwise direction. The cam 103 moves the cam follower 106, the rods 110 and 111, and the work-holder 116 to the left as the cam is rotated so that the cam follower 106 engages the periphery of the cam 106, which raises gradually from a depression 118 to the lobe 105, whereby any work positioned on the work-holder is moved at a uniform rate of speed to the left relative to the whipping head 25. The work-holder 116 is moved back to the right by the action of the compression springs 120—120 when the cam follower 106 passes over the lobe 105 and drops into a depression 117 formed on the periphery of the cam 103.

An adjustment screw 122 (Fig. 2) is secured on the end of the rod 111, and when the cam follower 106 engages the depression 117 or the depression 118 formed on the periphery of the cam 103, the screw 122 strikes a spring-pressed plunger 124 of a microswitch 125 and holds a contactor 126 (Fig. 5) of the microswitch out of engagement with contacts 130 and 131. When the cam 103 (Fig. 2) has been moved so that the cam follower 106 is out of engagement with both of the depressions 117 and 118, the screw 122 is moved away from the spring-pressed plunger 124 and permits the plunger to move the contactor 126 (Fig. 5) into engagement with the contacts 130 and 131. When the cam follower 106 (Fig. 2) next engages one of the depressions 117 and 118, the adjustment screw actuates the spring-pressed plunger 124 so that the plunger moves the contactor 126 (Fig. 5) out of engagement with the contacts 130 and 131 and holds it out of engagement therewith.

A supply reel 132 (Fig. 2) mounted rotatably on a holder 133 contains a supply of a whipping wire 134. The wire 134 is drawn through an opening 140 formed in a guide 136 (Figs. 2 and 4) of a tensioning device 135. The guide 136 is slidably mounted upon a rod 141 and is urged upwardly on the rod by a compression spring 142, which upward movement of the guide 136 is limited by a nut 143 threaded on the upper end of the rod 141. The guide 136 is secured against rotation on the rod 141 by keys 145—145 (Fig. 4) projecting from the guide into a keyway 144 formed in the rod 141. The wire 134 passes from the tensioning device 135, under a guide roller

146 (Fig. 2) and through a breaking mechanism 150 comprising a pair of spring-pressed discs, which are illustrated by a disc 147.

The wire 134 then is directed through the hollow shaft 22 to the whipping head 25 where it is accessible for whipping a conductor 157 of a cord 158 held on the work-holder 116, when the head 25 is rotated about the conductor 157 and the work-holder 116 moves the cord 158 away from the whipping head. When the whipping head 25 is rotated about the conductor, the wire 134 is wrapped around the conductor 157 in a close uniform spiral and is drawn from the supply reel 132, through the guide 136, under the roller 146, and through the braking mechanism 150, which places the wire under tension. The tensioning device 135 serves to maintain the wire 134 under tension, as the wire passes through the opening 140 in the guide 136 to the roller 146, in that the compression spring 142 urges the guide 136 upwardly. When the tension of the wire 134 is sufficiently great, the guide 136 is slid downwardly on the rod 141 against the action of the spring 142.

A circuit for controlling the operation of the apparatus described hereinabove is illustrated in Fig. 5, and includes a conventional timer 160 having a timer motor 161, which is connected to a power line 162 through a conductor 163 of the power line. The timer motor 161 also is connected to the power line 162 through a conductor 164, a safety switch 165, conductors 166 and 170, a contact 171 of a foot-operated switch 172, a contactor 173 of the switch 172, a contact 175 of the switch 172, and a conductor 176, which is connected to a conductor 180 of the power line 162. The foot-operated switch 172 includes a toggle actuating mechanism 174, which is designed, when actuated, to move the contactor 173 into engagement with the contacts 171 and 175 and lock the contactor 173 in that position. When the toggle mechanism 174 is again actuated it will move the contactor 173 out of engagement with the contacts 171 and 175, thereby breaking the circuit to the motor 161.

The timer 160 (Fig. 5) also includes a clutch coil 181 connected in parallel with the timer motor 161 by conductors 182 and 183, which are connected to the conductors 166 and 163, respectively. When the contactor 173 is in engagement with contacts 171 and 175, the clutch coil 181 is energized and moves a contactor 184 into engagement with a contact 185. The contactor 184 is connected to the conductor 180 of the power line 162 by a conductor 186, and the contact 185 is connected to a contact 191 by a conductor 190. A contactor 192 normally in engagement with the contact 191 is connected by conductors 193 and 194 to one end of the winding 70 of the solenoid 63, and a conductor 195 connects the other end of the winding 70 to the conductor 163 of the power line 162. The conductor 193 also connects the contactor 192 and the conductor 194 to the contact 130 of the microswitch 125, and the other contact 131 of the microswitch is connected by a conductor 196 to the conductor 190. A filament 200 of an incandescent lamp 201 is connected by conductors 202 and 203 to the conductors 170 and 163, respectively.

In the operation of the apparatus described hereinabove, the switch 17 (Fig. 1) is actuated to turn the motor 11 on, the cord 158 (Fig. 2) having the conductor 157, which is to be whipped, is positioned in the work-holder 116 and the end of the wire 134 is wrapped around the conductor 157. The foot-operated switch 172

(Fig. 5) then is actuated to move the contactor 173 into engagement with the contacts 171 and 175, and the toggle mechanism 174 latches the contactor 173 in that position. This closes the circuit to the motor 161 of the timer 160 and at the same time energizes the clutch coil 181, whereby the contactor 184 is moved into engagement with the contact 185. When the contactor 184 is engaged by the contactor 185, the winding 70 of the solenoid 63 is energized from the power line 162 through the conductors 180 and 186, the contactor 184, the contact 185, the conductor 190, the contact 191, the contactor 192, which is in engagement with the contact 190 at this time, and the conductors 193 and 194, and through the conductors 163 and 195.

When the winding 70 (Fig. 2) of the solenoid 63 is energized, the core 62 is drawn downwardly, whereby the driven clutch disc 35 is moved into engagement with the driving clutch disc 15, which is rotated continuously by the motor 11, the brake band 82 is moved out of braking engagement with the brake drum 33, and the lever 90 is drawn out of the path of rotation of the indexing lug 93. This causes the hollow shaft 22 and the whipping head 25 to be rotated and the wire 134 is wound upon the end of the conductor 157 of a cord positioned in the work-holder 116.

As the hollow shaft 22 (Fig. 2) is rotated, the worm gear 100 is rotated and turns the gear 101, thereby turning the shaft 102 and the cam 103. As the cam 103 is turned, the cam follower 106 is moved to the left, as viewed in Fig. 2, by the gradual rise on the periphery of the cam, thereby moving the work-holder 116 and the conductor 157 to the left at a uniform rate of speed. This causes the whipping head 25 to serve the wire 134 on the end of the conductor 157 in the form of an even spiral. Shortly after the rod 111 starts to move to the left, as viewed in Fig. 2, the adjustment screw 122 carried by the rod 111 is moved to the left sufficiently to permit the spring-pressed plunger 124 to move the contactor 126 (Fig. 5) into engagement with the contacts 130 and 131. Shortly thereafter the timer motor 161 causes the engagement between the contactor 192 and the contact 191 to be broken and to remain broken as long as the motor 161 continues to run. However, this does not cause the winding 70 of the solenoid 63 to be de-energized because the winding 70 then will be energized from the power line 162 through the conductors 180 and 186, the contactor 184, the contact 185, the conductors 190 and 196, the contact 131, the contactor 126, the contact 130, and the conductors 193 and 194, and through the conductors 163 and 195. That is to say, the microswitch 125 and the contactor 192 and the contact 191 are in parallel with the winding 70, and whenever the contactor 184 is in engagement with the contact 185 and either the microswitch 125 is closed, or the contactor 192 is in engagement with the contact 191, the winding 70 will be energized.

As the cam 103 (Fig. 2) continues to rotate, the cam follower 106 and the work-holder 116 continue to move to the left, as viewed in Fig. 2. However, when the cam follower 106 rides over the lobe 105 and is pressed into engagement with the depression 117, the work-holder 116 is snapped back into the position shown in Fig. 2, and the adjustment screw 122 engages the spring-pressed plunger 124 and moves the contactor 126 (Fig. 5) out of engagement with the contacts 130 and 131, whereby the circuit to the winding 70 of the solenoid 63 is broken.

The tension springs 64—64 (Fig. 1) then cause

the driven clutch disc 35 to be moved out of engagement with the clutch disc 15, the brake band 82 to be moved into braking engagement with the brake drum 33, and the arm 90 to be moved into the path of movement of the indexing lug 93. The brake band 82 then slows down the rotation of the brake drum 33 and the hollow shaft 22, which rotation is entirely stopped when the indexing lug 93 strikes the arm 90. However, any shock is prevented by the compression spring 94 (Fig. 3), which permits the shaft 91 and the arm 90 to give somewhat when the indexing lug 93 strikes the arm 90 but does so without interfering with the stopping of the rotation of the lug. Thus, the whipping head 25 is brought to rest in a position convenient to start another whipping operation.

The toggle mechanism 174 (Fig. 5) then is actuated to move the contactor 173 out of engagement with the contacts 171 and 175, whereby the timer motor 161 is de-energized, the lamp 201 is darkened, the clutch coil 181 is de-energized, which causes the contactor 184 to be moved out of engagement with the contact 185, the timer 160 resets to zero, and the contactor 192 moves back into engagement with the contact 191. The cord 158 and the conductor 157 just whipped then may be removed and the operations described hereinabove repeated upon the conductor of another cord.

The apparatus described hereinabove automatically applies whippings of uniform lengths and pitches to conductors of cords, such as the cord 158. It also discourages operators thereof from shortening the whippings of the conductors, since if the switch 172 is actuated to move the contactor 173 out of engagement with the contacts 171 and 175 before a whipping operation is stopped automatically, the timer 160 resets to zero, but the apparatus is in a point in its cycle in which a portion of the periphery of the cam 103 intermediate the depressions 117 and 118 engages the follower 106. In this position the spring-pressed plunger 124 maintains the engagement of the contactor 126 and the contacts 130 and 131, and shortly after the switch 172 is reclosed to start another whipping operation, the contactor 192 is moved out of engagement with the contact 191 so that the apparatus is stopped when one of the depressions 117 and 118 are engaged by the follower 106 and the adjustment screw 122 engages the plunger 124 to open the microswitch 125. This stops the apparatus, except for the motor 11 and the driving clutch disc 15, and the switch 172 must be reclosed if it is desired to continue the whipping.

Also, when the follower 106 is moved into engagement with one of the depressions 117 and 118 and the whipping is stopped, the work-holder 116 is moved back from its extreme left hand position to its extreme right hand position, as viewed in Fig. 2, and the conductor 157 being whipped also is moved to the right. Consequently, if the whipping is resumed on the partially whipped conductor, the subsequent whipping will overlap the previously applied whipping and may be detected easily by a supervisor. If further whipping is not conducted on the partially whipped conductor, the length of the whipping will be so short when compared with a whipping of normal length that it may be detected easily by a supervisor. Consequently, any tendency to shorten the whippings is prevented for all practical purposes. However, if an emergency arises, the apparatus

may be stopped by opening the switch 172 (Fig. 5).

The cam 103 can be replaced with others of different size and shape to vary the length and lay of the whippings applied by the whipping head 25. For example, if the length of whippings are to be shortened, a cam 303 having three lobes 304—304 (Fig. 6) thereon, may be substituted for the cam 103, the lobes 304—304 being smaller than the lobes 104 and 105. The number of teeth 108—108 (Fig. 2) on the gear 101 is an integral multiple of each of the various numbers of the lobes on the cams 103 and 303. Consequently, the number of teeth 108—108 are a multiple of six. Cams more than three lobes thereon also may be used if the number of teeth 108—108 is also a multiple of the greater number of lobes. Thus, regardless of which of the cams is used with the apparatus, in each whipping operation the adjustment screw 122 will strike the spring-pressed plunger 124 when the indexing lug 93 is in a predetermined point in a cycle of revolution thereof, whereby the brake band 82 always is moved into braking engagement with the brake drum 33 when the indexing lug has a predetermined portion of a revolution left to make before striking the arm 90. Consequently, the lug strikes the arm 90 with only a predetermined amount of force, which amount always is uniform. Thus, the apparatus may be utilized for whipping different types of cords which require different kinds of whippings on conductors forming parts thereof, but the whipping applied for any given type of cord will be uniform.

35. What is claimed is:

1. In a whipping apparatus, means for holding a conductor, a whipping head, means for rotating the whipping head around a conductor held by the holding means to wind a strand around the conductor, means for moving the holding means relative to the whipping head, and means for braking the rotating means after the holding means has been moved a predetermined distance relative to the whipping head.

45. 2. In a whipping apparatus, means for holding a conductor, a whipping head, means for rotating the whipping head around a conductor held by the holding means to wind a strand around the conductor, means for moving the holding means slowly in one direction relative to the whipping head, means for rapidly moving the holding means in the opposite direction, after the holding means has been moved a predetermined distance in the first-mentioned direction, and a brake for retarding the rotating means after the holding means has been moved a predetermined distance relative to the whipping head.

3. In a whipping apparatus, means for holding a conductor, a whipping head, means for rotating the whipping head around a conductor held by the holding means to wind a strand around the conductor, means for moving the holding means relative to the whipping head, a brake for retarding the rotating means after the holding means has been moved a predetermined distance relative to the whipping head, and means for stopping the whipping head in a predetermined position relative to the holding means.

4. In a whipping apparatus, means for holding a conductor, a whipping head, means for rotating the whipping head around a conductor held by the holding means to serve a strand upon the conductor, means for reciprocating the holding means relative to the whipping head to distribute the servings of the strand on the conductor, and

means for controlling the operation of the reciprocating means and the rotating means comprising a normally closed switch, means for opening the normally closed switch a few seconds after the start of a whipping operation, a second switch in parallel with the first-mentioned switch, and means associated with the reciprocating means serving to close the second switch just before the first-mentioned switch is opened and to open the second switch after the holding means has been reciprocated once, whereby the reciprocating means and the rotating means are stopped after the holding means has reciprocated once.

5. In a whipping apparatus, means for holding a conductor, a whipping head, means for rotating the whipping head around a conductor held by the holding means to serve a strand upon the conductor, means for reciprocating the holding means relative to the whipping head to distribute the servings of the strand on the conductor, and means for controlling the operation of the reciprocating means and the rotating means comprising a manually operable switch for starting the operation of the reciprocating and the rotating means, a normally closed switch, a timer for opening the normally closed switch a few seconds after the start of a whipping operation, a second switch in parallel with the first-mentioned switch, and means associated with the reciprocating means serving to close the second switch just before the first-mentioned switch is opened and to open the second switch after the holding means has been reciprocated once, whereby the reciprocating means and the rotating means are stopped after the holding means has reciprocated once.

6. In a whipping apparatus, means for holding a conductor, a whipping head, means for rotating the whipping head around a conductor held by the holding means to serve a strand upon the conductor, a cam, means associated with the rotating means for rotating the cam, a cam follower associated with the cam for reciprocating the holding means relative to the whipping head to distribute the servings of the strand on the conductor, means for driving the rotating means and the reciprocating means, a clutch interposed between the driving means and the rotating means and reciprocating means, and means for controlling the operation of the clutch including a solenoid, means operated by the solenoid for engaging the clutch when the solenoid is energized, a normally closed switch in series with the solenoid, means for opening the normally closed switch a few seconds after the start of a whipping operation, a second switch in parallel with the first-mentioned switch, and means associated with the cam follower serving to close the second switch just before the first-mentioned switch is opened and to open the second switch after the holding means has been reciprocated once, whereby the clutch is disengaged after the holding means has reciprocated once.

7. In a whipping apparatus, means for holding a conductor, a whipping head, means for rotating the whipping head around a conductor held by the holding means to serve a strand upon the conductor, means for reciprocating the holding means relative to the whipping head to distribute the servings of a strand being served by the whipping head upon the conductor, means for drawing the rotating and the reciprocating means, a brake for slowing the rotating means and the reciprocating means, means for stopping

the rotating means at a predetermined point in its rotation to index the whipping head relative to the holding means, actuating means serving to release the brake and indexing means when operated and to apply the brake and the indexing means when not operated, and means for automatically stopping the operation of the actuating means after a single reciprocation of the holding means.

10. 8. In a whipping apparatus, means for holding a conductor, a whipping head, means for rotating the whipping head around a conductor held by the holding means to wind a strand around the conductor, means for reciprocating the holding means relative to the whipping head, means for stopping the holding means and the rotating means, a solenoid serving to operate the stopping means when de-energized, timing means including a switch for energizing the solenoid when closed and means for opening the switch a few seconds after the timing means are energized, manually controlled means for controlling the energization of the timing means, a microswitch in parallel with the first-mentioned switch, and means associated with the reciprocating means serving to close the microswitch just before the first-mentioned switch is opened and to open the microswitch at the end of a single reciprocation of the holding means, whereby the solenoid is de-energized at the end of a single reciprocation of the holding means.

9. In a whipping apparatus, means for holding a conductor, a whipping head, means for rotating the whipping head around a conductor held by the holding means to serve a strand upon the conductor, means for reciprocating the holding means relative to the whipping head to distribute the servings of a strand being served by the whipping head upon the conductor, means for driving the rotating means and the reciprocating means, a clutch for connecting the driving means to the reciprocating means and the rotating means, a brake for slowing the rotating means and the reciprocating means, means for stopping the rotating means at a predetermined point in its rotation to index the whipping head relative to the holding means, actuating means serving to engage the clutch and to release the brake and indexing means when operated and to disengage the clutch and to apply the brake and the indexing means when not operated, a solenoid serving when energized to operate the actuating means, timing means including a switch for energizing the solenoid when closed and means for opening the switch a few seconds after the timing means is energized, manually controlled means for controlling the energization of the timing means, a microswitch in parallel with the first-mentioned switch, and means associated with the reciprocating means serving to close the microswitch just before the first-mentioned switch is opened and to open the microswitch at the end of a single reciprocation of the holding means, whereby the solenoid is de-energized at the end of a single reciprocation of the holding means.

10. 70. In a whipping apparatus, means for holding a conductor, a whipping head means for rotating the whipping head around a conductor held by the holding means to wind a strand around the conductor, a cam having a plurality of lobes formed thereon, a shaft for mounting the cam, a gear having a predetermined number of teeth formed thereon secured to the shaft, a second gear driven by the rotating means for

rotating the first-mentioned gear, whereby the cam is rotated, a cam follower for moving the holding means relative to the whipping head when the cam is rotated, means for stopping the rotating means, and means associated with the cam follower for actuating the stopping means when the whipping head is in a predetermined point in a cycle of revolution thereof, the number of teeth on the first-mentioned gear being an integral multiple of the number of lobes on the 10 cam.

11. In a whipping apparatus, means for holding a conductor, a whipping head, means for

rotating the whipping head around a conductor held by the holding means to wind a strand around the conductor, means for moving the holding means relative to the whipping head, a brake for stopping the rotating means after the holding means has been moved a predetermined distance relative to the whipping head, means for stopping the rotation of the whipping head in a predetermined position relative to the holding means, and means for actuating the brake when the whipping head is at a predetermined point in a revolution thereof.

ALEXANDER C. FRANKWICH.
